[57] CLAIM

The ornamental design for a medical treatment self-centering clamp, as shown and described.

DESCRIPTION

FIG. 1 is a first end view of a medical treatment self-centering clamp according to the present invention; FIG. 2 is a bottom view of a medical treatment self-centering clamp illustrated in FIG. 1;

FIG. 3 is a view of the right side of a medical treatment self-centering clamp as shown in FIG. 1;

FIG. 4 is a view of the left side of a medical treatment self-centering clamp as shown in FIG. 1;

FIG. 5 is a top view of a medical treatment self-centering clamp illustrated in FIG. 1;

FIG. 6 is a view of the end of a medical treatment self-centering clamp from the end opposed to that illustrated in FIG. 1;

FIG. 7 is a view of a medical treatment self-centering clamp illustrated in FIG. 1 moved to an open position; and,

FIG. 8 is a perspective view of a medical treatment self-centering clamp.
